Assistant Examiner — Lilyana Bekic

(57) **CLAIM**

The ornamental design for a drug delivery device, as shown and described.

DESCRIPTION

FIG. 1 is a top, left perspective view of a drug delivery device showing our new design;

FIG. 2 is a top, right perspective view of the drug delivery device of FIG. 1;

FIG. 3 is bottom, left perspective view of the drug delivery device of FIG. 1;

FIG. 4 is a top view of the drug delivery device of FIG. 1; FIG. 5 is a bottom view of the drug delivery device of FIG. 1;

FIG. 6 is a rear, end view of the drug delivery device of FIG. 1;

FIG. 7 is a front, end view of the drug delivery device of FIG. 1;

FIG. 8 is a right, side view of the drug delivery device of FIG. 1;

FIG. 9 is a left, side view of the drug delivery device of FIG. 1; and,

FIG. 10 is bottom, left perspective view of the drug delivery device of FIG. 1, showing an interlock portion in the retracted position.

The broken lines in the drawings depict portion of the drug delivery device that form no part of the claimed design.

1 Claim, 8 Drawing Sheets
